UNITED STATES PATENT OFFICE.

GUSTAV KOCH, OF NEW YORK, N. Y., ASSIGNOR TO THE EXPORT CORK AND SEAL COMPANY,
A CORPORATION OF NEW YORK.

CAP-CLOSURE FOR BOTTLES.

No. 888,621.

Specification of Letters Patent.

Patented May 26, 1908.

Application filed April 29, 1907. Serial No. 370,842.

To all whom it may concern:

Be it known that I, GUSTAV KOCH, citizen of the United States, residing at New York, in the county of New York and State of New York, have invented certain new and useful Improvements in Cap-Closures for Bottles, of which the following is a specification.

My invention relates to cap closures for bottles, and belongs to that class, examples of which are provided with a yielding disk of suitable material, usually cork, which is located within the cap and is pressed down upon the top of the bottle and held in position by bending a portion of the cap beneath an extending rim or the like formed integral with the bottle.

The object of my invention is the production of a cap for the purpose and of the nature stated, having special construction, and which may be released and removed from the bottle without the aid of a particular tool, and, in many instances, the cap is detachable with the fingers and no tool of any description is needed.

I accomplish the object stated by fashioning my invention in the form illustrated in the accompanying drawings, of which

Figure 1 represents the neck of a bottle with the cap set over the top. In this view the metal of the cap is not bent and the cap is not secured to the bottle. Fig. 2 is a vertical section of the neck of a bottle and the cap constituting my invention. In this view the metal of the cap is shown inwardly bent and the bottle closed. Fig. 3 is a representation of the neck of a bottle with the cap made in accordance with my invention set upon it and turned one-quarter way round from the position shown in Fig. 1. Fig. 4 is a vertical cross-section of part of the neck of a bottle and the cap in the positions shown in Fig. 3.

Like reference letters are employed to designate the same parts throughout the specification and claims.

The neck A of the bottle is formed with the customary annular rim α or in other desired shape.

I construct a cap B having its lower edge provided with a plurality of downwardly and outwardly projecting portions C. Through the wall of the cap, for example, at substantially equal distances apart slots D are formed, the ends of the slot opening into the larger circular orifices E. By forming the slot with

the orifices E as part thereof, the edges of the slot are to a greater extent and much more easily bent inwardly, because, only those edges are affected. Without the orifices E, any attempt to bend the edges of the slot inwardly to any extent results in tearing the adjoining metal, and the force required is much greater than is the condition with the orifices included.

The yielding or cork disk contained within the cap is marked F.

To operate my invention the cap is pressed downwardly upon the top of the bottle, and the cork disk compressed as shown in Fig. 2. The metal of the cap at the sides of the slots D is then forced inwardly beneath the rim α , which serves to hold the cap upon the bottle and the cork disk effectually in contact therewith. To remove the cap it is sufficient to press outwardly and upwardly upon either of the projecting portions C. This may be done by means of any utensil conveniently accessible at the time—a pocket knife or the end of a stick—practically any article may accomplish the purpose, and it is not at all a difficult matter to detach the cap in many instances simply with the fingers, by reason of the special construction above set forth.

Having now described my invention and explained the mode of its operation, what I claim is—

1. A cap closure having slots formed through its wall, the said slots opening at their ends into orifices of larger diameter than the width of the slot, and the edges of the slots between the said orifices adapted to be bent inwardly beneath the rim of a bottle to secure the cap, substantially as described.

2. A cap closure having slots formed through its wall, the said slots opening at their ends into orifices of larger diameter than the width of the slot, and the edges of the slots between the said orifices adapted to be bent inwardly beneath the rim of a bottle to secure the cap, and the edge of the cap being provided with one or more projecting portions, substantially as described.

3. A cap closure having slots formed through its wall, the said slots opening into orifices of larger diameter than the width of the slot, and the edges of the slots between the said orifices adapted to be bent inwardly

beneath the rim of a bottle to secure the cap, substantially as described.

4. A cap closure having slots formed through its wall, the said slots opening into orifices of larger diameter than the width of the slot, and the edges of the slots between the said orifices adapted to be bent inwardly beneath the rim of a bottle to secure the cap, and the edge of the cap being provided with

one or more projecting portions, substantially as described.

In testimony whereof I affix my signature in presence of two witnesses.

GUSTAV KOCH.
